W F Abbott
Grain Measurer

No. 74784

Patented Feb 25. 1868.

United States Patent Office.

W. F. ABBOTT, OF MARENGO, ILLINOIS.

Letters Patent No. 74,784, dated February 25, 1868.

IMPROVEMENT IN MEASURING AND TALLYING-ATTACHMENTS TO THRESHING-MACHINES.

The Schedule referred to in these Letters Patent and making part of the same.

TO ALL WHOM IT MAY CONCERN:

Be it known that I, W. F. ABBOTT, of Marengo, in the county of McHenry, and State of Illinois, have invented a new and improved Measuring and Tallying-Attachment for Threshing-Machines; and I do hereby declare that the following is a full, clear, and exact description thereof, which will enable those skilled in the art to make and use the same, reference being had to the accompanying drawings, forming part of this specification, in which—

Figure 1 is a front view of the elevator, with removed sections for exhibiting the grain-elevating mechanism.

Figure 2 is a vertical section of the measuring-chambers through the line $z z'$, fig. 3.

Figure 3 is a front elevation of the measuring-chambers, with a removed section of the casing covering the tallying-mechanism for exhibiting the latter.

Figure 4 is a horizontal section of the measuring-chambers through the line $y y'$, fig. 3.

Figure 5 is a horizontal section of the bifurcated spout through the line $z z'$, fig. 1, and also a top view of the measuring-chamber.

Similar letters of reference indicate corresponding parts.

This invention relates to a machine for measuring grain, and tallying the number of measures of the same which pass through it, and consists of an elevating-spout, measuring-chambers, and automatic tallying-register, which will now be more fully set forth.

The machine consists of two general parts, one being the elevating-box, having a bifurcated spout, shown at fig. 1; and the other consisting of two measuring-chambers, provided with the tallying-mechanism, as shown at fig. 3. These two figures represent the two parts in their relative size and position, the spout being above the measuring-chambers in the manner shown, so that each of its branches will discharge the grain into a measuring-chamber.

The measuring-chambers, as shown at fig. 3, when attached to the threshing-machine, occupy a position on the side of the threshing-machine, and between the front and rear wheel of the same. It can be attached thereto by metal straps or bolts, or in any suitable manner that will permit its removal, if desired. The part shown at fig. 1 is also attached in a similar manner to the same side of the threshing-machine, and in the relative position shown by the figs. 1 and 3. The lower end of the elevator-box will then reach down to the vicinity of the delivery-spout proper of the threshing-machine, which spout, as ordinarily placed, is at the rear end of the machine.

Instead of the grain being discharged into a half-bushel measure, or on the ground, as was the case heretofore, I join the said grain-spout to the end of my elevator-box in such a manner that the grain will be taken up by the buckets, revolving on a belt and pulleys within the elevator-box, and carried over into the junction of bifurcated spout aforesaid, from whence it falls into the branches of the same. This connection of the elevator-box with the grain-spout of the threshing-machine may be effected in several ways. For example, the lower end of the elevator-box may be plunged into a box into which the grain falls from the grain-spout, or a canvas sleeve may be made so as to connect the elevator-box and spout, or the spout may be made to open into the cavity of the elevator-box directly.

In the drawings, A is the elevator-box, with its pulleys P P, belt m , and grain-buckets $g g$, &c. This belt receives its motion from an exterior driving-pulley, P' , connected by belts, as shown, with some exterior pulley of the threshing-machine, which machines, as now generally built, afford ample facility for such connection. The lower end A'' of this box is connected with the grain-spout of the threshing-machine in some one of the ways above mentioned, so that, when the belt m revolves, the buckets g will fill with grain, and bear the same up to the junction B, where the grain will be spilled into the branches C C of the bifurcated spout, when the said buckets are in the act of passing over the upper pulley P .

Sliding doors D D, fig. 3, are pivoted to a lever, d , and this lever is pivoted centrally to a plate, d' , attached to the lower ends of the branches C C of the spout, as shown at figs. 1 and 3. Thus pivoted, the doors D D can be shut alternately to stop the egress of the grain from the branches, and the shutting one door opens the other, or the reverse.

When one of the measuring-chambers M is filled, its exit-door N is drawn outward by the handle n , thus exposing an opening, g , in the bottom of the chamber, through which the grain descends and passes out by the

spout N' located underneath the said opening, in the manner shown. In practice, sacks for receiving the grain are to be hung on the hooks shown attached to the spout. These chambers are lined with tin or zinc, and provided with an inclined diaphragm, f , of the same material, which is curved laterally, as indicated by the shading lines of the drawing, for the better delivery of the grain, for by this diaphragm all of the grain measured by the chamber will pass out, so that the entire contents of the chamber will be discharged, and by that means a given quantity of grain measured.

In practice, the capacity of these chambers is one bushel each, as a smaller unit measured is found, by experience, to involve loss, by the multiplication of an error of excess in each unit measure, where a large quantity of grain is handled by small measurements. This is a well-known fact in connection with the common half-bushel measure, and the want of an accurate and convenient measuring-device has long been felt by those interested, which want it is the object of this invention to supply, as well as to provide an automatic tallying-machine, for use in the same connection.

In operating my machine, while one branch of the spout is delivering, the other is closed to permit the undisturbed discharge of the measured grain from the chamber underneath the closed branch.

The discharge-openings of the measuring-chambers should be capable of passing out the grain equally as fast as the buckets g of the elevator can deliver it therein, and in practice it would be well to have this discharging-capacity somewhat greater than the threshing-capacity of the best machines, and, to do so, it is only required to provide a suitable area to the discharge-openings closed by the slide-doors N .

When one of the doors N is drawn out, as shown in fig. 4, the action of so drawing it out is made to operate the tallying-mechanism now to be described.

Each door N slides in slots in its spout N' , the said slots being cut in the side-boards of the spout, or made by nailing on strips of wood, as shown at p , fig. 2. Thus each door is held in smooth-sliding contact with the bottom of the chambers, and operates to close the discharge-openings in the manner shown. On the upper surface of these doors is a triangularly-shaped projection, as shown at i in figs. 2, 3, and 4.

A recess is cut in the under side of the bottom of the chamber, as shown at fig. 2, to accommodate this projection, so that the doors may fit closely to the said bottom, and also that the projection shall not prevent the door to which it is attached from being withdrawn in the manner before described, for the recesses extend outward to the front of the measuring-chamber. These projections are so located on their respective doors that, when one of the latter is withdrawn, the inner edge of the projections will impinge the corresponding end of the bar a , and actuate it horizontally to the right or left, as the case may be. This bar is held with loose contact in its slot by cross-pieces j, j , and the said slot is formed by a strip, o , secured against the bottom of the chambers, and by the side of a horizontal longitudinal recess made in the said bottom, and in which the bar a is allowed a short longitudinal movement, for a purpose to be shown. This bar a is shown in figs. 2, 3, and 4, where are also shown the pawls l pivoted to the bar at their lower ends.

When the bar a is moved to the right or left by the withdrawal of the right or left door, as the case may be, the pawl on that side is actuated to assume a more vertical position. In so doing, its point catches into one of the serratures of the double ratchet-bar h , and lifts the same upward a certain definite distance, which distance is made to correspond, by the arrangement of the mechanism, to certain tally-marks on the face of the vertical slotted case k attached as shown to the chambers. The ratchet-bar works within this case k , and is provided with a pin, s , which projects through the slot of the case, for the purpose of indicating, on the scale of tally-marks on the exterior of the case, and by the side of the slot, the height to which the ratchet-bar has been lifted. These tally-marks should number from one to a hundred, and be counted by figures at intervals of ten stamped on the case.

Thus, by the withdrawal of either one of the doors, the bar a is actuated laterally, and one of its pawls l made to catch in a serrature on the ratchet-bar, and lift the latter a certain distance, which distance brings the pin s to one of the tally-marks on the scale, and thus tallies one bushel more than was previously tallied, so that by each successive alternate withdrawal of the doors an additional bushel is tallied until the ratchet-bar is raised to the top of its travel, when a hundred bushels, or other number, according to the serratures of the ratchet-bar, and the corresponding tally-marks on the case, are indicated.

The points of the pawls l are pressed against the serratures of the ratchet-bar by springs q , arising from the screws r , in the manner shown, and held with tension against the ratchet-bar by means of the stud-pins t projecting from the exterior of the chamber.

Guides for the ratchet-bar are shown at u, u .

The staples v, v are for retaining the pawls and their springs in place.

The case k is screwed on to the measuring-chambers, as shown, and is made, in practice, of sheet brass.

When the ratchet-bar has been lifted to the extent of its travel, it is lowered by simultaneously turning in an outward direction the key-handles w, w , which lifts the springs clear of the serratures by means of the lifting-toe e (fig. 3) on each key, whereby the ratchet-bar descends by its own weight, to be again lifted.

B' is a door, hinged at b , catching by a slot over a staple, b' .

A' is a metallic door, fitting on the rounded ends A'' , and catching over a staple, as shown. These doors are for inspecting the interior of the machine in case there be any derangement of the internal mechanism of the same.

By the above specification, it will be seen that, when the tallying-mechanism is properly constructed, no grain can issue from the chambers without being duly registered or tallied, whereby the attendance of it can be entrusted to a boy, or any person having no special faculty for accuracy in tallying, as no mistakes can be made, and all uncertainty and dispute thereby avoided.

The mechanism of the machine is simple compared to the nature of its office, and the construction involving

no difficult or skilled workmanship, it can be made strong and efficient, and, at the same time, of reasonable cost.

The manner of operating this machine is as follows:

Sacks are hooked on to the hooks in the spouts N' , so that a spout is presented into each sack, the threshing-machine being then put in motion. One of the branches of the spout being closed, it is soon filled with grain, (for the latter is spilled from the buckets g into both branches,) and then all the grain spilled by the buckets passes down the open branch, and is delivered into the corresponding measuring-chamber. When this is filled, the branch of the spout then delivering grain is closed by pushing in its door D , which action opens the door D of the other spout. The grain lodged in this last-opened spout falls at once into the measuring-chamber, and a portion of the grain falling from the buckets g passes into the open branch, and an equal portion passes into the closed branch, until the latter is filled up to the junction of the branches, when all the grain spilled by the buckets is then delivered into the open branch. As soon as the branch over the filled measuring-chamber is closed, the door N of that chamber is drawn out, and the grain soon runs out into the bag, and is borne away while another bag is hooked.

The action of the tallying-mechanism has been described.

The bifurcated spout is removable, being held to the part B of the elevator-box by a staple and hasp on each side, one of which is shown.

A piece of canvas can be placed so as to protect the open space between the spout and measuring-chambers from the chaff and dirt blowing therein, if used in windy weather.

I claim as new, and desire to secure by Letters Patent—

1. The elevator-box A , pulleys F F , belt m , and buckets g , in combination with the bifurcated spout C C' , doors D D , measuring-chambers M , and doors N N , all constructed, arranged, and operating substantially as set forth.

2. The combination of the pivoted doors D , pivoted lever d , and plate d' with the bifurcated spout C C' and measuring-chambers M , substantially as and for the purposes set forth.

3. The combination of the sliding bar a , pivoted pawls l , doors N , having projections i ; double ratchet-bar h , springs q , pointer s , and register k , substantially as described and represented.

4. In combination with the above, I claim the key w , substantially as described and for the purpose specified.

5. The doors D , substantially as shown and described, in combination with the bifurcated spout C and measuring-chambers M , for the purpose of alternately opening and closing said spout, all as set forth.

6. The projections i , in combination with the discharge-door N of a grain-measuring chamber, substantially as shown; and for the purpose specified.

7. The bar a and its pawls l , in combination with the ratchet-bar h and projections i , or other equivalent device, substantially as shown and described, and for the purpose set forth.

8. The ratchet-bar h , in combination with the tally-scale of the case k , substantially as shown and described, for the purpose of tallying grain, all as set forth.
